Inventor:

JACOB WIKETTE,

By John N. Brumaga.

His Attorney.

UNITED STATES PATENT OFFICE.

JACOB WIKETTE, OF ST. LOUIS, MISSOURI.

TOY CANNON.

1,183,940.

Specification of Letters Patent.

Patented May 23, 1916.

Application filed June 25, 1915. Serial No. 36,288.

To all whom it may concern:

Be it known that I, JACOB WIKETTE, a subject of the King of Hungary, but having declared my intention to become a citizen of the United States, and residing at St. Louis, in the State of Missouri, have invented a certain new and useful Improvement in Toy Cannon, of which the following is a specification.

This invention relates to toy cannons of the type embodying a barrel having a plunger movably mounted therein and actuated under influence of a spring or springs for forcibly expelling a projectile from said barrel, together with means for latching the plunger in retracted or projectile expelling position.

The invention has for its objects to provide an inexpensive toy of this character which will simulate in appearance the modern type of ordnance having recoil cylinders at the sides of the barrel; one wherein the actuating springs are housed within the cylinders and connected for imparting a maximum expelling force to the plunger; one in which the plunger may be readily retracted against the influence of the springs and automatically latched in retracted position; and one wherein the latch keeper may be readily and positively actuated for releasing the plunger.

Further objects of the invention are to simplify the construction of toys of this type by providing one in which the parts may be readily and inexpensively produced and assembled, and one having a simplified form of latching means which will, however, automatically and effectually latch the plunger in its retracted position.

With these and other objects in view, the invention comprises the novel features of construction and combination of parts more fully hereinafter described.

In the accompanying drawing, Figure 1 is a side elevation of a toy cannon embodying the invention; Fig. 2 is a horizontal longitudinal section taken on the line 2-2, Fig. 1, parts being shown in plan; Fig. 3 is a rear detail elevation, partly in section; Fig. 4 is a detail transverse section taken on the line 4-4, Fig. 2; Fig. 5 is a detail section on the line 5-5, Fig. 1; and, Fig. 6 is a detail perspective view of the latch keeper.

Referring to the drawings, it will be seen that the carriage, which is mounted on an axle 1 equipped with wheels 2, comprises

side members or arms 3, and a trail 4, these parts, with the exception of the axle, being suitably formed from sheet metal.

Sustained on the carriage is a barrel 5 having side cylinders 6 disposed respectively at opposite sides, and to extend longitudinally of the barrel throughout a suitable portion of its length, these cylinders, which represent the recoil cylinders of the modern type of ordnance, being closed at their ends, while formed in the adjacent walls of the cylinders and barrel are longitudinal slots 7. The barrel, which, together with the cylinders, is composed of metal tubing, has its rear or breech end closed by means of a cap 8, while extending transversely through the cylinders, adjacent their forward ends, are pins 9.

Housed respectively in the cylinders 6 are a pair of coiled tension springs 10, engaged, at their forward ends, with the pins 9, and, at their rear ends, with portions or arms 11 formed on a plunger 12 movably mounted in the barrel 5 and arranged to play in the slots 7, there being connected with the plunger, which carries a latch piece 13, a retracting member 14, preferably composed of a length of wire bent into substantially elongated U-shape, and having its side portion or arms, which play through perforations in the cap 8, attached, at their forward ends, to the plunger, and with its rear looped portion projecting beyond the rear end of the barrel to present a finger piece or loop 15.

The latch piece 13, which is preferably struck from the material of the plunger 12, is adapted, when the plunger is moved to retracted position, to engage a keeper 16 rotatably mounted upon one face of the breech cap 8, and equipped with a pair of spaced forwardly projecting engaging portions 17 having undercut notches 18 and oppositely inclined cam faces 19 adapted to be acted upon by the part 13 for rotating the keeper to permit the part 13 to pass between the members 17 and seat within the notches 18. Fixed upon the rear end of the keeper pintle 20 is a finger piece or arm 21 projecting loosely through a U-shaped guide 22 attached to the cap 8 and acted upon by a leaf spring 23 attached, at one end, to the outer end of the arm, and having bearing, at its other end, in the guide 22, this spring serving to maintain the keeper normally in engaging position.

Attached to the trail 4 at a point adjacent

the rear end of the cannon, is a bracket 24, through which is threaded the lower end of a screw 25 rotatably mounted in a bracket arm 26 attached to one of the carriage members 3, there being mounted on said screw, which is provided, at its upper end, with a knurled head 27, a spring 28 having bearing, at its ends respectively, against the bracket arms 24 and 26.

10 In practice, supposing the parts to be in the position as illustrated in Fig. 2, the loop 15 may be engaged by the finger of the operator for actuating the member 14 to retract the plunger 12 against the action of springs 10, which will, of course, as the plunger moves rearward to retracted position, be expanded or tensioned. As the plunger nears the limit of its rearward movement, the latch piece 13 comes into contact with the oppositely beveled faces of the keeper portions 17, and acts upon these cam faces to automatically rotate the keeper against the action of spring 23 sufficiently to permit the part 13 to pass between the keeper arms 17 to a position opposite the undercut notches 18, whereupon the spring 23 will throw the keeper to engaging position with the part 13 seated in said notches. A marble or other suitable projectile is then placed in the barrel, and by a proper manipulation of the finger piece 21, which simulates the breech lever of a real cannon, the keeper is thrown to position for releasing the latch piece 13 to permit the springs 30 10 to actuate the plunger for forcibly expelling the projectile, as will be readily understood. It is to be particularly noted that, by the provision of the cylinders 6, the appearance of the toy is made to more nearly 35 simulate that of an actual modern cannon, and further, that, through the provision of these cylinders, the device may be readily equipped with a pair of springs, lending a greater expelling force to the plunger, and further, that the springs can thus be so arranged that the force which they exert upon the plunger may be properly equalized to insure a smooth even movement of the plunger under the action of the springs. It is 40 also to be noted that the mouth of the cannon may, by proper manipulation of the screw 25, be readily elevated or depressed at will, to vary the range of the projectile.

It is obvious that various changes may be 45 made in the details of construction without departing from the spirit of this invention. It is, therefore, to be understood that this invention is not to be limited to the specific construction shown and described.

50 Having thus described the invention, what is claimed is:

1. A toy cannon comprising a carriage, a barrel mounted on said carriage and having

a side cylinder outside of the barrel and simulating the recoil cylinder of a modern field piece, a plunger movably mounted in the barrel, and means housed in the cylinder for actuating said plunger to expel a projectile from the barrel.

2. A toy cannon comprising a carriage, a barrel mounted on said carriage and having side cylinders outside of the barrel and simulating the recoil cylinders of a modern field piece, a plunger movably mounted in the barrel, and means housed in the cylinders for actuating said plunger to expel a projectile from the barrel.

3. A toy cannon comprising a carriage, a barrel mounted on said carriage and having side cylinders outside of the barrel and simulating the recoil cylinders of a modern field piece, a plunger movably mounted in the barrel, means housed in the cylinders for actuating said plunger to expel a projectile from the barrel, and means including a breech lever for latching the plunger in projectile expelling position.

4. A toy cannon comprising a barrel, a plunger movably mounted therein, means adapted to actuate the plunger for expelling a projectile from the barrel, and means for releasably latching the plunger in projectile expelling position, said means consisting of a rotatable keeper having oppositely cammed engaging portions, a part on said plunger adapted to act on said cammed portions for throwing them automatically into engagement with said part, and means for moving the keeper to releasing position.

5. A toy cannon comprising a barrel, a plunger movably mounted therein, means adapted to actuate the plunger for expelling a projectile, a keeper rotatably mounted at the rear end of said barrel and having oppositely cammed engaging portions, a part on the plunger adapted to act on said cammed portions for throwing them automatically into engagement with said part, a spring for maintaining the keeper normally in engaging position, and a finger piece for moving the keeper against the action of said spring.

6. A toy cannon comprising a barrel, a plunger movably mounted therein and having a latch part, means adapted to actuate the plunger for expelling a projectile, a keeper movably mounted on the barrel and having oppositely cammed engaging portions disposed to be acted upon by said latch part for throwing said portions automatically into engagement therewith, a spring arranged for maintaining the keeper in engaging position, and means for moving the keeper against the action of said spring.

In testimony whereof I affix my signature this 7th day of June, 1915.

JACOB WIKETTE.
